(57) **CLAIM**

The ornamental design for a display screen with an animated graphical user interface, as shown and described.

DESCRIPTION

FIG. 1 is a first image in a sequence for a display screen with an animated graphical user interface showing a first embodiment of our new design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a first image in a sequence for a display screen with an animated graphical user interface showing a second embodiment of our new design;

FIG. 8 is a second image thereof;

FIG. 9 is a third image thereof;

FIG. 10 is a fourth image thereof;

FIG. 11 is a fifth image thereof; and,

FIG. 12 is a sixth image thereof.

The appearance of the animated graphical user interface sequentially transitions between the images of the first embodiment shown in FIGS. 1-6, and the appearance of the animated graphical user interface sequentially transitions between the images of the second embodiment shown in FIGS. 7-12.
